UNITED STATES PATENT OFFICE.

FRANCIS J. VAN DOREN, OF LANSDOWNE, PENNSYLVANIA, ASSIGNOR TO GILLINDER & SONS, INC., OF PHILADELPHIA, PENNSYLVANIA, A CORPORATION OF PENNSYLVANIA.

DESIGN FOR A GLASS SPINDLE.

40,524.

Specification for Design.

Patented Feb. 22, 1910.

Application filed December 24, 1909. Serial No. 534,898. Term of patent 14 years.

To all whom it may concern:

Be it known that I, FRANCIS J. VAN DOREN, a citizen of the United States, and resident of Lansdowne, in the county of Delaware and State of Pennsylvania, have invented a new, original, and ornamental Design for a Glass Spindle, of which the following is a specification, reference being had to the accompanying drawing.

In said drawing Figure I is a view in side elevation of my new design, and Fig. II an end view thereof.

The spindle is made of clear or transparent glass, roughed, ground, or frosted to render it opaque, semi-opaque or translucent.

I claim—

The ornamental design for a glass spindle as shown and described.

FRANCIS J. VAN DOREN.
